UNITED STATES PATENT OFFICE.

JULIUS J. MELMS AND CHARLES E. WALLACE, OF DETROIT, MICHIGAN; SAID MELMS
ASSIGNOR TO SAID WALLACE.

DESIGN FOR A RING.

Application filed April 21, 1924. Serial No. 9,338. Term of patent 7 years.

To all whom it may concern:

Be it known that we, JULIUS J. MELMS and CHARLES E. WALLACE, citizens of the United States, residing at Detroit, in the county of Wayne and the State of Michigan, have invented a new, original, and ornamental Design for Rings (Case C), of which the following is a specification, reference being had to the accompanying drawing, forming part thereof.

Fig. 1 is a perspective view of a ring showing our new design thereon.

Fig. 2 is a detailed sectional perspective view of our ring showing a cross sectional contour thereof.

We claim:

The ornamental design for a ring as shown.

Detroit, Mich., April 15th, 1924.

CHARLES E. WALLACE.
